UNITED STATES PATENT OFFICE.

PATRICK GORMLEY, OF STURGEON BAY, WISCONSIN.

DESIGN FOR A CHURN-DASHER.

SPECIFICATION forming part of Design No. 30,068, dated January 24, 1899.

Application filed December 31, 1898. Serial No. 700,860. Term of patent 14 years.

To all whom it may concern:

Be it known that I, PATRICK GORMLEY, a citizen of the United States, residing at Sturgeon Bay, in the county of Door and State of Wisconsin, have invented and produced a new and original Design for a Churn-Dasher, of which the following is a specification.

This invention relates to a new and original design for a churn-dasher; and it has for its object to provide a design of this character that shall be both useful and ornamental.

The leading feature of the design resides in a skeleton frame having a plurality of spaced straight longitudinal slats arranged in parallel relation, and a pair of shorter cross-slats intersecting the longitudinal slats at right angles and spaced a distance apart, the said cross-slats being respectively arranged near the opposite ends of the longitudinal slats and upon opposite sides of the latter.

While the essential feature of the design resides in the above-specified relation of the longitudinal and cross slats, it is to be noted that the minor features of the design are having the outer longitudinal slats of equal length and the intermediate longitudinal slat of a shorter length than said outer slats and terminating short of the ends of the latter.

Additional minor features of the design are the cross-slats being of a greater length than the distance between the outer longitudinal slats, so as to project beyond the plane of the latter, and all of said slats being of a flat cross-sectionally rectangular shape.

In the drawings, Figure 1 is a perspective view of a churn-dasher embodying the herein-described design. Fig. 2 is a plan view thereof.

Referring to the accompanying drawings, the numeral 1 designates the complete churn-dasher, which consists of a skeleton slatted frame having a plurality of spaced straight longitudinal slats 2 and 3 arranged in parallel relation and of a flat cross-sectionally rectangular form. The outer longitudinal slats 2 of the slatted frame are of equal length and have their ends disposed in the same transverse plane, while the intermediate longitudinal slat 3 is of a shorter length than the outer or side slats 2 and terminates short of the ends of the latter.

In addition to the parallel longitudinal slats 2 and 3 the skeleton frame of the dasher is provided with a pair of shorter cross-slats 4, also of a flat cross-sectionally rectangular form. The said cross-slats 4 intersect the longitudinal slats 2 and 3 at right angles thereto and are respectively arranged near opposite ends of the several longitudinal slats and upon opposite sides of the latter. The said cross-slats 4 are also of a greater length than the distance between the outer or side longitudinal slats 2, so as to project beyond the plane thereof.

What is claimed is—

The design for a churn-dasher, herein shown and described.

In testimony that I claim the foregoing as my own I have hereto affixed my signature in the presence of two witnesses.

PATRICK GORMLEY.
